UNITED STATES PATENT OFFICE

ORDA D. NUTTER, OF PARKERSBURG, WEST VIRGINIA, ASSIGNOR TO ACME FISHING TOOL COMPANY, OF PARKERSBURG, WEST VIRGINIA, A CORPORATION OF WEST VIRGINIA

FISHING SPEAR

Application filed May 29, 1929. Serial No. 366,805.

This invention relates to fishing tools of the type known as casing spears used for the removal of pipe sections or casings from a well.

5 In devices of this character it is essential that they be capable of adjustment, that is, that the serrated slips thereof have a range of expansion such that casings of different inside diameters may be gripped thereby. It is 10 one of the objects of this invention, therefore, that a simple means of adjustment be provided for determining the amount of expansion which the slips may have.

It will be apparent that a considerable 15 amount of wear and tear takes place in the use of a tool of this description and that the tool as a whole must be of a very rugged construction. It is, therefore, necessary that every weak portion be eliminated and a maximum strength secured.

One of the difficulties experienced in tripping or releasing spears is due to the fact that the seats upon which the slips slide or move are of substantially the same extent as the 25 slips themselves, so that when a slip in expanding moves longitudinally of its seat, a portion of the slip projects beyond the seat and is not supported thereby. Under these circumstances the resistance of the casing to this unsupported portion of the slip frequently 30 causes a distortion or even breakage of the lower portion thereof. It is then not possible to trip the spear in the event that the casing cannot be started, and the spear is consequently 35 jammed within the pipe. It is, therefore, one of the objects of this invention to overcome this effect.

Another important object is to overcome 40 the defect of the Boardman spear wherein the body itself is weakened at the extreme top portion of the slip seat due to the fact that an unnecessary amount of metal has been removed from the body or stem. In the device of this present invention maximum thickness 45 of spear body is provided so that there is no weakness at that point.

To this end the invention includes a tool 50 body having slip seats thereon of a greater longitudinal extent than the slips which slid- ily interlock therewith so that throughout

the effective longitudinal movement of each slip, it is entirely underlaid by a seat surface. Both slips and seats are provided with abutting curved portions which engage each other when the slips are in the inoperative position, 55 thus strengthening the body to a material extent.

Below the slips is a push up ring having fingers projecting upwardly and engaging the bottom of the slips to move them into inoperative position under impulse of a coiled spring on which the push up ring rests. This push up ring may carry means whereby it may be latched to the spear body.

It is sometimes desirable to place a plain 65 ring member between the fingered ring and the coiled spring, this plain ring member being rotatably and slidably mounted on the body and carrying the latching means. In both cases, the spring encircles the body and 70 is held between a spear head or cone nut and the ring.

The invention further consists in the novel arrangement, combination and construction of parts more fully hereinafter described and 75 shown in the drawings.

In the drawings:

Fig. 1 is an elevation of a spear embodying this invention, with the slips in the inoperative position.

Fig. 2 is a sectional view along the line 2—2 of Fig. 1.

Fig. 3 is a sectional view along the line 3—3 of Fig. 1.

Fig. 4 is a longitudinal sectional view of a 85 slip.

Fig. 5 is a top plan view of a slip.

Fig. 6 is an elevation partly in section of a device with the slips in expanded position.

Fig. 7 is a view of a modified form of the 90 invention.

Referring now with particularity to the embodiment illustrated, there is shown at 1 an elongated body having at the top thereof a tapered threaded portion 2 for attachment to 95 the usual tool string.

A portion of the body is fashioned to form a plurality of slip seats, four being shown, each of which consists of a plane portion 3 interrupted by a dovetailed groove 4, the 100

upper portion of the surface 3 merging with a curved portion 5 which is a part of a substantially cylindrical surface.

The curved portion makes unnecessary the carrying back of the plane surface which would weaken the body at the juncture with the enlargement 6. As a result, this curved portion adds material strength to the body and provides a tool having maximum ruggedness.

Slips 7 are provided, corresponding in number to the seats, each slip being adapted to engage and longitudinally move upon a seat. The slips consist preferably of a segment of hardened metal having a serrated outer face 8 for engagement with the inside of a casing, and being backed with a projection 9 of a configuration corresponding to that of the dovetailed groove 4, and for engagement therewith. As shown, each slip is, therefore, keyed to its seat in a manner to prevent outward or radial movement except as it is a component of the desired longitudinal movement. An important requisite resides in the fact that each seat 3 is of greater longitudinal extent than its slip, so that within the operative range of slip movement, the entire slip is at all times entirely underlaid and supported by its seat surface and breakage or distortion of the lower end of the slip cannot occur.

In Fig. 1, which is the inoperative position of the assembly, it will be noted that the slips 7 are in their extreme upward location, and the curved tops thereof fit and abut snugly the similarly shaped portions 5 of the body.

It is also to be noted that the slips are tapered from top to bottom so that as they move upon their seats in a downward direction they expand to engage the casing, the outer portion of the slips maintaining a substantially parallel relation to the wall of the casing within which the device operates. The serrated teeth 8 on outer portion of each slip are adapted to bite into the inner surface of the casing when the slips are in their operative or expanded position.

Below that portion of the body forming the slip seats is a stem 10 threaded at the lower end thereof to receive a cone nut 11 made secure to the stem by means of a pin 12 passing through the nut 11 and the end of the stem. The hole for the pin 12 is put through the blank portion of stem 9 below the threads to prevent injury to the threads on the stem or cone nut. This head or cone nut is substantially tapered at the lower end thereof in order to facilitate entry of the tool into the casing.

A recess 13 is provided in the upper portion of the nut 11 to accommodate a coiled spring 14 seated between the head and encircling the stem.

A push up ring 15, recessed as at 16 to receive the top of the spring 14, encircling the

stem 10 and resting upon the top of the spring 9 is provided with a series of upwardly extending fingers 17, each of which projects within a channel 18 which intersects the plane surface of the slip seats 3. Each finger 17 engages the bottom or lower portion of a slip 7.

The spring 14 is of such a size and extent that in its expanded position it will force the ring 15 upwardly and the fingers thereof will push each slip in the same direction until the curved top portion thereof is abutting the similarly shaped portion 5 of its seat. This is the inoperative position of the slips and is shown in Fig. 1, inasmuch as under these circumstances their outer surfaces 8 are substantially flush with the outer surfaces of the tool body.

In order to permit the slips to move downwardly and thus expand against the inside of the casing without opposing the action of the spring, a slip setting latch or trip may be provided in the push up ring. This latch may conveniently take the form of a stud 19, located within a recess in the push up ring 15. The stud is provided with a frustro conical end portion 20 adapted to enter a recess 21 in the stem 10, the wall of the recess being adapted to overhang and engage the portion 20 of the stud. A coil spring 22 surrounds the stud 19 and bears against the head 23 thereof, thus tending to retract the stud from the stem 10. A cap 24 threaded to the recess in the push up ring 15, retains the parts therein. An aperture 25 in the cap permits the stud to be latched to the body by inserting a tool or nail therethrough.

As shown, a plurality of such stem recesses are provided, the overhanging walls thereof being at different vertical heights. This permits of various adjustments.

Taking the spear from the position shown in Fig. 1, the push up ring 15 may be drawn down against the action of the spring 14 by any suitable means, until the stud 19 is opposite its recess 21. By then inserting a nail through the aperture in the cap 24, the end 20 may be forced under the overhanging wall of the recess, and the upward thrust of the spring 14 will retain it there. In this position, the fingers 17 are withdrawn from the bottom of the slips and the latter permitted to drop down in their seats, with a consequent expanding action. This allows the spear to be lowered within a casing, but when an upward movement is imparted to the string, the serrated face of the slips bites into the casing and further upward movement of the spear causes an expansion of the slips to a desired extent.

Obviously the slips may move downwardly to any extent, being limited only to either the diameter of the well casing, or the distance between the bottom of the push up ring 15 and the top of the cone nut 11.

To release the spear from the casing, it is only necessary to cause a downward movement of the push up ring in relation to the spear body so as to permit the latch spring 22 to withdraw the latch stud 19 from the stem recess. When this action has taken place, the spring 14 will force the push up ring 15 upwardly, the fingers 17 thereof pushing the slips 7 into the inoperative position 10 of Fig. 1. The spear may then be freely withdrawn from the casing.

Obviously any desired form of latch means may be used other than that shown, and a plurality of setting positions may be provided, such as is possible with the construction shown in the Boardman patent supra.

It may be desirable to provide an additional element to carry the latching means, such for instance as shown in Fig. 7. This 20 consists of a plain ring member 26, without fingers, in which a latch assembly is located, the ring being positioned between the spring 14 and the push up ring 15 and encircling the stem 10.

25 In operation the latch having been set in the proper position, the tool is lowered into the well until the casing to be pulled or adjusted is reached. The slips will drop down into their expanded position due to the fact 30 that the spring 14 is slightly compressed. However, when the casing is reached, the slips will be forced upwardly thereby and will finally occupy a retracted position within the casing. Upward movement of the tool 35 will cause a downward movement of the slips and their serrated faces will bite into the inner walls of the casing and securely grip the same. This downward movement of the slips also causes downward movement of the 40 ring carrying the latch permitting the latch mechanism to release. In this position the casing can be pulled out of the well along with the tool string. When it is desired to release the spear from the casing it is only 45 necessary to jar the spear in a downward direction which movement will free the serrated teeth of the slips from the inside wall of the casing, and the spring 14 will, through the train of cooperating parts, force the slips 50 upwardly to occupy an inoperative position. The tool may then be withdrawn from the casing.

An important feature of the invention consists in making the ring fingers of greater 55 vertical extent than the permitted vertical movement of the ring. This is for the sole purpose of preventing, when the fingered ring is drawn to its lowermost position, the accidental withdrawal of the fingers from 60 their grooves. Due either to the fact that the bottom of the fingered ring or the second ring contacts with the upper portion of the cone nut or the compression spring when fully contracted will not permit these surfaces to contact, downward movement of the 65

fingers and the element carrying them is limited. It is, therefore, desirable that this downward movement be arrested at a point where the fingers will not come completely out of their respective grooves. This point 70 may be readily determined and compensated for by screwing the cone nut 11 further up on the threads of the body so as to produce the desired effect. At any rate, it is desirable that the fingers shall be of a greater vertical 75 extent than their permitted vertical movement, and this is an important feature of the invention.

I claim:

1. A fishing spear comprising a body having slip seats thereon, slips on the seats, a push-up ring below the slips having fingers engaging the bottom of the slips, a nut on the bottom of the body, a tension spring between the nut and the push-up ring, the ring fingers being of greater vertical extent than the permitted vertical movement of the ring. 80

2. A fishing spear comprising a body, a slip seat thereon, a slip on said seat, a nut on the bottom of the body, a spring resting on the nut, a ring engaged by the top of the spring and a finger engaging the bottom of the slip and urging the slip upwardly on its seat under action of the spring, the finger being of a greater vertical extent than the permitted vertical movement of the ring. 90

In testimony whereof, I have hereunto subscribed my name this 21st day of May, 1929.
